UNITED STATES PATENT OFFICE

2,206,796

VENETIAN BLIND

Lisle C. Williams, Memphis, Tenn.

Application September 14, 1939, Serial No. 294,952

4 Claims. (Cl. 156—17)

The present invention relates to new and useful improvements in Venetian blinds and has for its primary object to provide, in a manner as hereinafter set forth, a device of this character comprising novel means through the medium of which the blinds may be expeditiously and firmly secured in position in a window, particularly the lower portion thereof.

Other objects of the invention are to provide a blind of the aforementioned character which will be comparatively simple in construction, strong, durable, highly efficient and reliable in use, compact, light in weight, attractive in appearance, and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a view in front elevation of a Venetian blind constructed in accordance with the present invention, showing the device installed in a window with the slats in open position.

Fig. 2 is a view in vertical section through the blind.

Fig. 3 is a vertical sectional view through the upper portion of the blind, taken at right angles to Fig. 2.

Fig. 4 is a horizontal sectional view, taken substantially on the line 4—4 of Fig. 3.

Fig. 5 is an elevational view of the upper portion of a slight modification, showing the sockets or brackets in vertical section.

Fig. 6 is an elevational view of one of the sprockets or brackets.

Fig. 7 is a view in end elevation of one of the rails, showing the slidable rod in cross section.

Referring now to the drawings in detail, it will be seen that the reference numerals 1 and 2 designate upper and lower rails which, of course, may be of any suitable material, preferably wood. Connecting the rails 1 and 2 are ladder tapes 3 comprising straps 4 of suitable flexible material between which cross straps or members 5 extend at spaced points. Mounted on the cross straps 5 are slats 6. The slats 6 have formed therein transverse slots 7 (see Fig. 4) which accommodate lengths of cord 8 having their end portions secured to the rails 1 and 2, as at 9. It may be well to here state that the cords 8 simply secure the slats 6 against longitudinal movement in the ladder tapes 3.

The rails 1 and 2 have formed in one end portion longitudinally extending sockets 10 which terminate in reduced inner end portions 11. This is shown to advantage in Fig. 3 of the drawings. The sockets 10 are closed by apertured plates 12 which are secured on one end of the rails 1 and 2. Slidably and rotatably mounted in the sockets 10 are rods 13 which project through the apertures provided therefor in the plates 12. The inner end portions of the rods 13 are slidably engaged in the reduced portions 11 of the sockets 10.

Mounted on the outer end portions of the rods 13 are suction cups 14 of rubber or other suitable resilient material. Fixed on the rods 13 and operable in the sockets 10 are collars 15. Coil springs 16 encircle the rods 13 in the sockets 10. The outer ends of the coil springs 16 are engaged with the collars 15 for yieldingly urging the rods 13 outwardly. The inner ends of the coils 16 bear 20 against the shoulders 17 which are formed by the reduced portions 11 of the sockets 10 in the rails 1 and 2.

The other end portions of the rails 1 and 2 have formed longitudinally therein sockets 18. 25 Mounted in the outer portions of the sockets 18 are bushings 19 in which rods 20 are threaded for longitudinal adjustment. Mounted on the outer end portions of the adjustable rods 20 are suction cups 21.

It is thought that the manner in which the blind functions will be readily apparent from a consideration of the foregoing. Of course, the suction cups 14 and 21 are engageable with the opposed sides of the window frame 22 in a manner to firmly but removably secure the rails 1 and 2 in position therebetween. By simply rocking the rails 1 and 2 on the elements 13 and 20, the slats 6 may be conveniently tilted as desired. The coil springs 16 cause the suction cups 14 and 21 to firmly grip the sides of the window frame. The threadedly mounted rods 20 permit adjustments to be conveniently made for positioning the blind centrally in windows of different widths. To remove the blind from the window, 45 it is only necessary to slide the rods 13 inwardly in the rails 1 and 2 against the tension of the coil springs 16.

Referring now to Figs. 5 to 7, inclusive, of the drawings, it will be observed that brackets or 50 sockets 23 are provided in lieu of suction cups for supporting the rails 1 and 2 in position in the window frame. The brackets 23 are of suitable metal and comprise substantially U-shaped intermediate portions 24 having apertures or 55

openings 25 therein. The portions 24 of the brackets 23 terminate in feet 26 which are mounted on thrust plates 27. Screws 28 in the end portions of the brackets 23, firmly secure said brackets in position on the opposed sides of the window frame 22. In this form of the invention the outer end portions of the elements 13 and 20 are adapted to enter the openings 25 in the brackets 23 and engage the plates 27. This is shown to advantage in Fig. 5 of the drawings.

It is believed that the many advantages of a Venetian blind constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A Venetian blind comprising upper and lower rails, ladder tapes connecting said rails, slats mounted in said ladder tapes, each rail having a socket in one end portion, each socket terminating in a reduced inner portion providing a shoulder in the rail, an apertured plate mounted on said one end of the rail over the socket, a rod slidably mounted in the socket and projecting through the plate, the inner end portion of said rod being engaged in the reduced portion of the socket, a collar fixed on the rod and operable in the socket, and a coil

spring encircling the rod in the socket and having one end engaged with the shoulder and its other end engaged with the collar for yieldingly urging the rod outwardly for engagement with one side of a window frame. 5

2. A Venetian blind comprising upper and lower rails, ladder tapes connecting said rails, slats mounted in said ladder tapes, said rails having longitudinal sockets in one end portion thereof, bushings mounted in the sockets, rods 10 threadedly mounted in said bushings, and suction cups on said rods engageable with a window frame for securing said one end of the rails thereto.

3. A Venetian blind comprising a rail, rods 15 slidably mounted in the end portion of said rail and projecting longitudinally therefrom, and brackets adapted to be mounted on a window frame for supporting the rail thereon, said brackets including substantially U-shaped, apertured intermediate portions for the reception of the rods and further including thrust plates traversing the U-shaped portions and engageable by the outer ends of the rods. 20

4. A Venetian blind comprising upper and lower rails, rods carried by the end portions of said rails and projecting therefrom, suction cups connected with the outer ends of the rods, spring means for forcing one rod of each rail outwardly, flexible members extending between the rails and 30 connected therewith and slats connected with said flexible members.

LISLE C. WILLIAMS.
